KNIT GARMENT AND METHOD OF MAKING
SAME

Louis A. Kesselman, Long Beach, N. Y.

Application May 3, 1937, Serial No. 140,399

5 Claims. (Cl. 66—176)

This invention relates in general to a new and improved method for making a fashioned knit garment, and in particular to a new method for attaching sleeves to bodies in knitted wear whereby sagging and bagging of the cloth at the shoulder is eliminated, the garment is made to look and wear better, and the cost of production is materially lessened.

By its very nature knitted wear is made of very resilient material which has a tendency to stretch and sag and become baggy in the wearing. This tendency is exaggerated in loose and ill fitting garments, and conversely, is lessened and can be neutralized in the well fitting and shaped garments.

In the making of knitted sweaters, for instance, fashioning or shaping of the garment is very necessary at the sleeves where they are attached to the shoulders. In knitting a sweater by hand, 10 stitches can be easily picked up or dropped, the knitted body can be widened or narrowed, as the case may require, to achieve the fashioning or shaping desired. Not so in the mass production of the same by machinery. I know of no machine, used in the manufacture of knit garments en masse, that will automatically pick up or drop 15 stitches to make a fashioned product.

The general commercial practice is to knit the sweaters on reciprocating, flat-bed knitting machines. The body is usually made in two sections, front and back, the sides and top of the same are then sewn together, the neck is cut out and trimmed, and then the sleeves are sewn on either with or without cutting the body material to narrow the shoulders.

Cutting back the material of the body where the sleeve attaches produces a better fitting garment because that is what gives the fashioning at the shoulders and chest. Where this is not done, and it usually is not for the cheaper trade, the upper part of the seam between the body and the sleeve does not rest on the shoulder of the wearer but lies on the side of the arm. The effect is not only a baggy appearance when the 20 garment is new, but the material tends to stretch so that with wear the seams move down to a lower position on the arm to increase the shabbiness. When the armhole is cut out of the body portion of the garment, the cutting usually follows an arcuate path which has no special relation to the weave in the garment.

It is a common practice, in order to lessen the sag of the armhole seam, to reinforce the sweater with a less elastic material placed on the shoulder, epaulet fashion, between the seam and

the neck. The reinforcement generally is in the form of a knitted strip of the same yarn as the body, but knitted with a less resilient stitch. This method, however, does not completely eliminate the defect.

There are skilled workmen engaged in the knit sweater industry who can manually knit two pieces of knit cloth together so that for all practical purposes the result is a homogeneous piece; that is, none but the experienced will recognize the seam as such. These people produce seamless sweaters, so to speak, wherein the sleeves are manually knitted to the body. In this method the shoulder material can not be cut back because that will produce a lot of free ends, 10 and the process requires either loops or selvage at the joining edges. Eliminating the seam, however, does not eliminate the sagging and stretching shoulder.

A full fashioned garment can be made on an 20 automatic knitting machine in the following manner: Each time the cloth is to be made narrower the machine must be stopped, the end needle must be removed by hand and its loop transferred to the adjacent needle before the machine 25 is started up again. If the cloth is to be widened the machine must also be stopped to permit the manual insertion of the extra needles or needle. This process is laborious and is not used in mass production systems.

It is the principal object of this invention to provide a method of producing a fashioned sleeve junction on a knitted garment with the aid of automatic machinery quickly and cheaply.

It is a further object of this invention to facilitate the production of hand fashioned (so called in the art) knitted garments.

The primary feature of this invention is that by its use a shoulder fitting garment is produced.

Another feature of my method lies in that by 40 its use a visible seam at the arm pit can be eliminated.

Another feature of my invention lies in the means devised to insure uniformity of cut-backs at the shoulders for the sleeve insets.

Still another feature of my invention is the pleasing effect of the ultimate result produced by its use.

Additional objects and features of the invention will become apparent from the following 50 specifications and the accompanying drawing, in which:

Fig. 1 shows a knit sweater, laid out flat, with the right sleeve attached, and the left sleeve about to be,

Fig. 2 is a perspective view of a sleeveless sweater showing how the edges of the arm-hole, cut as I propose, fall in the same plane when the garment is worn.

Fig. 3 is an enlarged detail of a simple knit cloth illustrating my method of mechanically delineating the sleeve juncture while the body portion of the sweater is being knit.

Knitted cloth can be considered as made up of a long single thread looped and interlocked with itself in successive courses. In Fig. 1, line 1 is an approximation of the locus of the thread at a given course in the body 2 of a knitted garment. If the cloth is cut parallel to this course, the thread is cut at each of its loops into very small bits. These bits of thread are easily removed so that the loops of the next course are exposed and free. However, if the cloth is cut at an angle to line 1, the thread is cut at each succeeding course. Essentially, my new and improved method consists in taking the body portion of a knitted garment which is knit unfashioned on a knitting machine, cutting out a substantially rectangular piece at the shoulder, and attaching the sleeve to the edges thus exposed, a portion of the cutting being along a course.

In Fig. 1 the shaded area 3 is the piece of cloth cut out; edge 4-5 is cut parallel to the knitted courses; edge 5-6 is cut across the courses. The knitted sleeve 7 is so made that the shoulder end 8 has either a looped or selvage edge. The sleeve is attached to the body 2 by manually knitting end 8 to edge 4-5 and sewing the remainder of end 8 to edge 5-6. The result is illustrated at the right hand of Fig. 1. The visible seam is shown at 9; no seam is apparent at the armpit 10.

The principal feature of this method resides in that part of the armhole seam is along and parallel with the knitted courses in the body of the garment. This permits a portion of the sleeve to be attached by knitting means. However, the entire sleeve may be sewn to the body along the lines 4-5-6 (lines 4-5-6-5' in Fig. 2) without reducing the fashioning effect. Fig. 2 illustrates, in perspective, a sleeveless garment made up of a front portion 11 and a back portion 12 with the armhole 4-5-6-5' cut as I have indicated. It should be noted that when the garment is worn all the edges of the armhole are in the same plane with the armpit. It is not essential however that this be so; line 5-6 need not be cut perpendicular to line 4-5.

In cutting knitted cloth there is always the danger that the loose ends and loops set free will unravel and spoil the entire piece of cloth. In quantity production I first attach the sleeve to the body and cut out the superfluous matter afterward. Average skilled workmen in the art can turn the body and sleeve inside out, pick out the loops in the body that are to be knitted to the sleeve, knit them to the sleeve and then sew the remaining portion up on a machine or by hand; the superfluous portion of the body is then cut out. I prefer to leave a margin of body material when cutting along the sewn portion of the seam to allow the said material to be turned back on itself and sewn again to anchor the free ends of the yarn more firmly.

To facilitate attaching the sleeves by this latter method, and to insure uniformity of size and sleeve inset in the product the knitting machine should be made to delineate the seam 4-5-6. Most knitting machines are adapted to do this.

In Fig. 3 is shown an enlarged detail of a knitted cloth taken in the vicinity of the armhole.

The stitch illustrated is known as a plain stitch. At the place, 13, where the horizontal portion, 4-5 in Fig. 1, of the arm seam is to come the machine is made to change from plain stitch to purl stitch. Similarly, where the machine is to mark out the sewn portion 14 of the seam it is made to make a purl stitch; so too, is it made to show the line 15 along which the cutting is to be done. The type of stitch is not material, the principal requirement is that it be recognizable; and a loose stitch is preferable. In the illustration the change in type makes the delineating stitches stand out in relief. I prefer to have the entire operation of attaching the sleeve to the body done by hand, both the knitting and the sewing, with the yarn as thread and the stitches of the attaching operation connecting directly with the loops in the body material that is made to stand out in relief. But again, this is not essential to my method.

In the illustration, Fig. 3, the knitting of the fabric has proceeded in horizontal courses from the top down. The upper left-hand corner of the illustration, bounded at the bottom by line 13 and at the right by line 15, corresponds to the shaded portion 3 in Fig. 1.

It is possible to produce on an automatic knitting machine a garment body wherein the shoulder already has the shape required for my method of sleeve attachment: The machine is allowed to knit the body portion up to the line where the armhole begins. The machine is stopped, the number of needles required to produce the necessary inset are removed from the needle bed, their loops caught up and prevented from unraveling by inserting a piece of yarn or wire or by any other means known to the art, and then the machine is allowed to finish knitting the body portion. By this method the entire armhole 4-5-6-5' has either a looped or selvage edge, and the sleeve can be knitted on so that no portion of the seam need be sewn.

My method of attaching sleeves to knitted garments, and the steps necessary to attain the fashioning effect produced thereby will be readily understood from the foregoing description, and it will be seen that I have provided a simple, inexpensive and efficient process for carrying out the objects of my invention. Furthermore, while I have particularly described the elements best adapted to perform the functions set forth, it is obvious that various changes in form, proportion, and in minor details of production may be resorted to without departing from the spirit or sacrificing any of the principles of the invention.

What I claim is:

1. In the production of a knitted garment, where the body portion is made with excess material at the armhole and the attachment of the sleeve to the body is a separate operation, the method of securing uniformity in size and shape of the armhole seams comprising delineating by a change in stitch in the body portion the location of said seams, a portion of said delineation being along a course in the knitted garment and the remaining portion being substantially perpendicular to said course.

2. A method of producing a knit outer garment with sleeves comprising knitting the body portion with excess material at the armhole and delineating the location of the armhole seam by a change in stitch concurrently therewith, attaching the sleeve to the said body portion along the line indicated, and then removing the said excess

- material in the body portion; a portion of said delineating line being along a course in the body portion, and the remainder of said delineating line being substantially perpendicular to said course.
- 5 3. A knit outer garment with sleeves in which an armhole seam in both the front and back portions of the garment is along two lines substantially perpendicular to each other; one of said lines being along a course in the body of the garment and the sleeve is attached therewith by knitted means, the remainder of the seam being a sewn seam along the line substantially perpendicular to said course.
- 10 10 4. The method of attaching the sleeve to the

body portion of a knit garment comprising knitting a portion of said sleeve to the body portion along a course therein, and sewing the remainder of said sleeve to the said body portion along a line substantially perpendicular to said course.

5 5. The method of attaching the sleeve to the body portion of a knit garment, said body portion having been formed with excess material at the armhole, comprising knitting a portion of said sleeve to the body portion along a course therein, sewing the remainder of said sleeve to the body portion along a line substantially perpendicular to said course, and then removing the said excess material.
